UNITED STATES PATENT OFFICE.

BYERS W. KADEL, OF BALTIMORE, MARYLAND, ASSIGNOR, BY MESNE ASSIGNMENTS,
TO THE SYMINGTON COMPANY, A CORPORATION OF MARYLAND.

SPRING PLANK.

Application filed October 25, 1923. Serial No. 670,656.

My invention relates to an improved spring plank construction for use in connection with car truck side frames and contemplates the production of a comparatively light weight 5 casting of maximum strength value adapted to embrace neighboring portions of the side frame and distribute the loads to the frame at points best able to stand them.

One of the principal features of the invention is to provide a spring plank seat member 10 designed to distribute the loads to the inner and outer walls of a wrought metal side frame, the underside of said member being spaced from the major portions of inwardly 15 extending stiffening flanges formed on the side walls whereby said flanges are relieved for the most part of the vertical loads, the reducing in thickness of the body portion of the seat member between the portions 20 thereof which contact the side frame being compensated for by reinforcing means in the nature of a projection depending from the undersurface of the seat member and extending between the inner and outer walls of the 25 side frame.

Another object of the invention resides in the provision of a spring plank saddle casting adapted to embrace the beam member of the side frame and contact the same at spaced 30 intervals, the contact points being preferably located adjacent the corner bends of the bolster opening at the junction of the beam member and truck columns, intermediate portions of the saddle casting being disposed in spaced 35 relation from the central portion of the beam member but capable of engaging the same for transmitting excessive loads to the side frame.

A further feature of the invention is to produce a spring plank seat casting of great 40 strength value, said casting having a body portion provided with a longitudinally disposed depending rib designed to extend between the inner and outer walls of a car truck side frame, said rib acting to reinforce 45 the body portion of the casting for resisting the loads imparted through the bolster springs, said loads being distributed through the portions of the casting contacting the side frame, which portions mainly overlie 50 the inner and outer walls.

Another object of the invention resides in the production of a casting for a car truck side frame adapted to be connected to a spring 55 plank and embrace neighboring portions of the frame, said casting having spaced projec-

tions resting upon the side frame, and a reinforcing projection of relatively increased depth disposed between the aforesaid projections, said casting being provided with upstanding transversely disposed ribs uniting 60 the portions embracing the side frame and being relatively enlarged at points disposed in longitudinal alignment with the reinforcing projection to which they are connected.

A still further object of the invention is to 65 provide a spring plank construction involving a saddle casting and spring plank connected to an inwardly extending projection thereof, said casting having longitudinally extending depending portions designed to embrace 70 adjacent portions of the side frame at the bottom of the bolster opening, the inner opposed faces of said depending portions being formed so as to permit the casting to fulcrum with relation to the side frame in resisting 75 loads, said movement serving to reduce the shear strains upon the rivets connecting the spring plank to the casting.

The invention has for another object the provision of a spring plank construction in- 80 volving a saddle casting and a relatively short spring plank, said plank being connected to an inwardly projecting portion of the casting, which portion is reinforced by a rib forming 85 a gusset between the rivets connecting the spring plank to the projecting portion.

A still further object of the invention is to provide a saddle member having a spring 90 plank seating surface, said surface being surrounded by upstanding walls which, in addition to retaining the springs in position, also serve to greatly strengthen the member.

The invention further resides in the particular combination, details of construction and arrangement of the several parts to be 95 hereinafter referred to.

In the drawings illustrating my invention, the scope whereof is pointed out in the claims:

Figure 1 is a fragmentary view of a car truck side frame showing my improved spring 100 plank saddle member applied thereto.

Figure 2 is a top plan view thereof, portions of the side frame being shown in horizontal section.

Figure 3 is a vertical transverse sectional 105 view through the beam portion of the side frame and saddle member positioned thereon said view being taken on the line 3-3 of Figure 2, looking in the direction of the arrows.

Figure 4 is a detached view in end elevation of the saddle member.

Figure 5 is a detail view of a portion of the saddle member in vertical longitudinal section.

Figure 6 is a view in side elevation, partly in section of a modified construction of saddle member and spring plank shown applied to a car truck side frame.

10 Figure 7 is a top plan view thereof, with adjacent portions of the side frame being shown in horizontal section.

Figure 8 is a detail vertical cross sectional view on the line 8-8 of Figure 7.

15 Referring to the drawings in which similar reference characters designate corresponding parts in the several views, my improved spring plank construction is shown applied to a wrought metal side frame having an inner

20 wall 1 and an outer wall 2, each of said walls being formed with top arch bar portions forming the compression member, bottom arch bar portions continued beneath the bolster opening to form a beam member, and

25 truck column portions uniting the compression and beam members of the side frame. The truck columns are indicated by the numeral 3 and the beam member by the numeral 4, the spring plank saddle casting or

30 seat member 5 being positioned upon the beam member and embracing the inner and outer walls of the side frame, as shown.

In my present construction the inner and outer walls of the side frame are provided

35 with inwardly extending stiffening flanges, said flanges bordering the top arch bar portions, bottom arch bar portions, and truck column portions, the flanges on said portions adjacent the bolster opening being designed

40 to surround or border said opening. The column stiffening flanges are designed to merge into connecting flanges 6 which border the lower end of the bolster opening, said flanges heretofore being adapted to receive

45 the vertical loads imparted to the side frame through the seat casting.

My present construction of spring plank saddle member has been designed to distribute the vertical loads to the inner and outer walls of the side frame without increasing the relative thickness of the body portion of the seat casting or reducing the depth of the beam member of the side frame, it being obvious that in the maintaining of

55 the relative thickness of the body portion of the saddle casting that the depth of the bolster opening will remain constant. The body portion of the seat casting 5 is provided with projections 7 at each end thereof, said

60 projections being adapted to rest upon the inwardly extending stiffening flanges 6 at their junctions with the stiffening flanges of the truck columns. The projections 7 mainly rest upon the side frame portions at the junction of the inwardly extending stiffening

flanges and the inner and outer walls respectively, said projecting portions being outwardly flared at these junction points so as to overlie relatively large portions of the inner and outer walls, as best shown in Figure 2.

The underface of the seat member is provided with a projection 8 of relatively less depth than the projection 7, said projection being disposed transversely of the seat member and adapted to contact the stiffening flanges when excessive loads are received. In addition, this relatively short projection 8 serves to reinforce the relatively thin body portion of the casting transversely thereof. Portions of the projections 7 are relatively reduced in cross sectional area, as indicated at 9, these reduced portions permitting of an increased depth of beam member at the critical points of the side frame.

The upper surface of the saddle casting in

85 the construction shown in Figures 1 to 5, inclusive, is designed to receive a spring plank, an upstanding annular rib 10 being provided on said surface adapted to form a pivot boss for co-action with the spring plank. De-

pending longitudinally extending ribs or flanges 11 project from the underface of the body portion of the casting, said flanges being adapted to embrace neighboring portions of the car truck side frame. The flanges 11

55 are braced by angular webs 12 connecting the body portion therewith. The ends of the flanges 11 are continued upwardly at each end of the seat member and form bracing webs

13 for the upstanding ribs or flanges 14 disposed transversely of the seat member at each end thereof. The transverse upstanding ribs 14 unite the depending flanges 11

60 at each end of the seat member and act to transfer the lateral loads to said flanges 11 longitudinally of the side frame. The intermediate portion of the transverse flanges 14 is relatively enlarged, as indicated at 15, said enlargement being disposed in central longitudinal alignment with a main reinforcing

65 rib 16, the upstanding ends of which are connected to said enlarged portions.

The reinforcing rib 16 depends from the underface of the body portion of the saddle member, said rib being preferably located centrally thereof and of a depth greater than the depending side flanges 11. The rib 16

70 extends the full length of the casting and is designed to reinforce the relatively thin cross sectional area lying between the projecting portions 7 and 8. A reinforcing flange 17 is

75 preferably provided along the lower edge of the rib 16, said flange being preferably increased in width centrally of the casting, as shown. Vertically disposed bracing ribs 18

80 unite the projecting portions of the flange 17 to the web section of the rib 16 and the body portion of the casting. The vertical loads imparted through the bolster springs

85 to the body portion of the casting are trans-

mitted through the contacting projections 7 to the side frame, the loads intermediate said projections being resisted by the reinforced intermediate portion of the casting and transmitted to the sides thereof overlying the inner and outer walls of the frame.

Referring to Figures 6 to 8, inclusive, there is illustrated a modified construction of spring plank saddle casting in which a relatively short spring plank 19 is employed, said plank being connected to the underface of an extension 20 projecting inwardly of the side frame from the body portion 21 of the saddle casting. A plurality of rivets 22 rigidly connect the spring plank to the extension or projection 20, said rivets being located upon opposite sides of an upstanding rib 23 uniting the upstanding transversely disposed ribs or flanges 24 arranged at each end of the casting. The upstanding rib 23 is angularly disposed with respect to the longitudinal alignment of the connecting rivets 22, said rib passing between alternate rivets and forming a gusset construction of maximum strength value. The innermost ends of the upstanding transverse ribs 24 are continued inwardly beyond the gusset-like rib 23 to the innermost edge of the extension 20, thereby reinforcing the metal along one side of the rivet opening. The inner edge of the extension 20 may be cut away toward the intermediate point-like portion of the upstanding rib 23, as shown.

The depending longitudinally extending flanges 25 of the modified construction have their inner opposed faces shaped so as to provide intermediate fulcrum points 26 about which the casting is capable of rocking with respect to the side frame. The opposed inner faces of the flanges are outwardly flared toward each end thereof, the intermediate portions providing extensions about which the casting may swing in resisting the loads. This rocking movement is desirable in that it allows angling of the spring plank so as to progressively resist the loads and reduce the shear strains upon the rivets rigidly connecting said spring plank to the projection or extension 20. The outer longitudinally extending flange 25 is preferably braced by the angular web adjacent the fulcrum point, as shown.

The longitudinally disposed reinforcing rib 27 depends from the body portion of the casting and serves to reinforce the relatively thin cross sectional area of said body portion between the projections 28 contacting the flanges of the side frame. The lower edge of the reinforcing rib 27 may be suitably flanged, as indicated at 29.

The outer edge of the modified construction of saddle casting is provided with an upstanding wall 30, said wall acting to retain the bolster springs in position. The wall 30, transversely extending ribs 24, and

the upstanding reinforcing rib 23 provide an upstanding enclosure bordering the spring seating surface, said construction adding to the strength value of the casting.

A spring plank construction involving a saddle casting constructed in accordance with the present invention is comparatively light in weight and of great strength value, it being understood that my particular construction is capable of use with types of side frames other than that described wherein it is desirable to relieve portions of the beam member of the side frame of the vertical loads and at the same time provide a casting of sufficient strength value while maintaining a constant depth of bolster opening, maximum depth of beam member and the required rail clearance. It will be observed from the present construction that the principal reinforcing rib is let down between the inwardly extending stiffening flanges of the side frame, which flanges are sufficiently spaced from the body portion of the saddle casting as to prevent their deformation under service conditions.

I claim:

1. The combination with a car truck side frame having inner and outer walls each of which is provided with a bolster opening and an inwardly extending stiffening flange adjacent the bottom of said opening, of a spring plank saddle member having portions of its underface designed to engage said flanges and other portions of said underface spaced therefrom, and means provided on the underface of said member for reinforcing the same, said means serving to compensate for the relatively reduced thickness of said member at the portions spaced from said flanges.

2. The combination with a car truck side frame having inner and outer walls each of which is provided with a bolster opening and an inwardly extending stiffening flange adjacent the bottom of said opening, of a spring plank saddle member having portions of its underface designed to engage said flanges and other portions of said underface spaced therefrom, but capable of engaging said flanges in resisting excessive loads, and means provided on the underface of said member for reinforcing the same.

3. The combination with a car truck side frame having inner and outer walls, each of said walls having a bolster opening and an inwardly extending stiffening flange adjacent the bottom of said opening, of a spring plank saddle member having portions of its underface adapted to rest upon the side frame at the junction points of the side walls and stiffening flanges, and other portions of said member spaced therefrom, and reinforcing means for the saddle member disposed between the inwardly extending flanges of the side frame.

4. The combination with a car truck side

- frame having inner and outer walls, of a spring plank saddle member having its underface formed with spaced projections adapted to rest upon portions of the side frame overlying the inner and outer walls respectively, said saddle member having another projection adapted to extend between said inner and outer walls, said last named projection acting to reinforce the relatively reduced thickness of the saddle member at the portions thereof not contacting the side frame.
5. The combination with a car truck side frame having inner and outer walls, of a spring plank saddle member having a portion forming a spring plank seating surface and an underface provided with spaced projections contacting the side frame, and means extending from the underface of said saddle member adapted to reinforce the same, said means serving to compensate for the relatively reduced cross sectional area of the saddle member adjacent the spring plank seating surface and lying between said spaced projections.
10. The combination with a car truck side frame having spaced portions forming inner and outer walls, of a spring plank member having portions adapted to embrace said walls and other portions adapted to contact the side frame at spaced intervals, and means including a depending rib adapted to reinforce the spring plank member between the inner and outer walls of the side frame.
15. The combination with a car truck side frame, of a spring plank member having portions adapted to embrace the inner and outer side walls of the frame, said member being formed with projections adapted to contact the side frame at spaced intervals, and another projection forming a reinforcing rib for the portion of the spring plank member lying between the said portions contacting the side frame.
20. The combination with a car truck side frame, of a spring plank member having portions adapted to embrace the inner and outer side faces thereof, said member being formed with projections adapted to contact the side frame at spaced intervals, another projection forming a reinforcing rib depending from the spring plank member and extending between the portions thereof contacting the side frame, and a reinforcing flange provided on said depending rib.
25. The combination with a car truck side frame having inner and outer walls, each of said walls being formed with a bolster opening and having a plurality of top arch bar portions, a plurality of bottom arch bar portions, and a plurality of truck column portions, of a spring plank seat member having portions adapted to embrace the side frame beneath the bolster opening, said member having projecting portions adapted to contact the side frame at the junction of the truck column portions and bottom arch bar portions, and means reinforcing said spring plank member between the portions contacting the side frame.
30. The combination with a car truck side frame having inner and outer walls arranged in spaced relation, each of said walls having a bolster opening and being provided with top arch bar portions, bottom arch bar portions, and truck column portions, of a spring plank saddle member having portions adapted to embrace the side frame beneath the bolster opening, said member having portions on its underface adapted to contact the side frame transversely of the bolster opening at the junction of the truck column portions and bottom arch bar portions, and reinforcing means for said saddle member including a depending portion extending longitudinally thereof between the portions of the member contacting the side frame.
35. The combination with a car truck side frame having a bolster opening, of a spring plank saddle member provided with depending longitudinally extending flanges embracing the side frame at the bottom of said opening, and means provided on the inner opposed faces of said flanges intermediate the ends thereof adapted to form fulcrum points about which the saddle member may move.
40. The combination with a car truck side frame having a bolster opening, of a spring plank saddle member supporting said spring plank, said saddle member having a portion forming a fulcrum point between the ends thereof for permitting the same to rock with respect to the side frame in a substantially horizontal plane.
45. The combination with a car truck side frame having a bolster opening, of a relatively short spring plank, a spring plank saddle member having an inwardly extending portion alone connected to the spring plank, and fulcrum means arranged between said saddle member and side frame for permitting relative rocking movement therebetween.
50. The combination with a car truck side frame having a bolster opening, of a spring plank, a spring plank saddle member, means rigidly connecting said spring plank to the spring plank saddle member, and a fulcrum arranged between said saddle member and side frame for permitting horizontal angling of the spring plank with respect to said frame.
55. The combination with a car truck side frame having a bolster opening, of a relatively short spring plank, a spring plank saddle member, the upper face of which forms a spring seat, a projection formed on said saddle member, rivet means connecting one end of the spring plank to said projection inwardly of the spring seating surface, and fulcrum means arranged between the opposite

ends of said saddle member for permitting relative movement thereof with respect to the side frame.

16. The combination with a car truck side frame having a bolster opening, a relatively short spring plank, a spring plank saddle member embracing the side frame at the bottom of the bolster opening and being provided with an inwardly extending projection, means connecting said spring plank to said projection, and means including a rib reinforcing said inwardly extending projection, said rib being disposed in alternate relation between the means connecting the spring plank to said projection.

17. The combination with a car truck side frame having a bolster opening, of a spring plank, a spring plank saddle member embracing the side frame at the bottom of the bolster opening and being provided with a horizontally disposed inwardly extending projection, rivet means connecting the spring plank to said projection, and means including an upstanding diagonally arranged rib provided on said projection for reinforcing the same adjacent the rivet connection.

18. The combination with a car truck side frame having a bolster opening, of a spring plank, a spring plank saddle member embracing neighboring portions of the side frame at the bottom of the bolster opening, rivet means connecting the spring plank to said saddle member, reinforcing means provided on the saddle member adjacent the rivet connection, and fulcrum means arranged between the saddle member and side frame for permitting relative movement therebetween whereby the loads are progressively imparted to the side frame with minimum shear strains upon the rivet connecting means.

19. The combination with a car truck side frame having a bolster opening, of a spring plank saddle member embracing neighboring portions of the side frame at the bottom of the bolster opening and having an inwardly projecting portion angular in cross-section, a spring plank, means connecting the spring plank to the underface of said projecting portion, and means reinforcing said projection, said reinforcing means involving an upstanding rib disposed in close proximity to said connecting means.

20. A spring plank saddle casting having a body portion formed with a plurality of projections extending from the underface thereof, some of said projections being adapted to engage a neighboring portion of a car truck side frame for transmitting the vertical loads thereto, and at least one of said projections being adapted to reinforce said body portion between the projections engaging the side frame.

21. A spring plank saddle casting having a body portion of relatively thin cross sectional

area, said body portion being formed with depending longitudinally extending ribs adapted to embrace neighboring portions of the car truck side frame and having projecting portions adapted to engage the frame at spaced intervals for transmitting vertical loads thereto, and means including a rib projecting from the underface of the relatively thin portion of said casting and disposed between the portions contacting the side frame for reinforcing the body portion of the member and permitting of uniform distribution of the loads throughout the same.

22. A spring plank saddle casting provided with a body portion of relatively thin cross sectional area, a projection extending from the underface of said body portion and adapted to engage neighboring portions of the side frame for imparting vertical loads thereto, a centrally located longitudinally extending depending rib projecting from the underface of said casting for reinforcing the body portion thereof, and means including a flange adapted to reinforce said depending rib.

23. A spring plank saddle casting comprising a body portion having longitudinally disposed depending flanges adapted to embrace neighboring portions of the car truck side frame, a projection provided on the underface of said casting between said depending flanges and adapted to contact adjacent portions of the side frame, a reinforcing rib for said body portion disposed longitudinally of the casting between said depending flanges, and transversely extending upstanding flanges arranged at each end of the casting, said flanges being designed to intersect the longitudinally extending reinforcing rib and adapted to unite said depending flanges.

24. A spring plank saddle casting comprising a body portion having depending longitudinally disposed flanges designed to embrace neighboring portions of the car truck side frame, projections extending from the underface of said member between the depending flanges adapted to contact adjacent portions of the side frame for imparting vertical loads thereto, a reinforcing rib for said body portion extending longitudinally of the casting between said depending flanges, transversely extending upstanding flanges arranged at each end of the body portion of the casting and having their intermediate portion relatively enlarged, said enlarged portions being disposed in longitudinal alignment and connected to said reinforcing rib.

25. A spring plank saddle member comprising a body portion having depending flanges adapted to embrace opposite side faces of the car truck side frame, the inner opposed faces of said flanges providing fulcrum points between the ends of the member for permitting relative rocking movement between the saddle member and side frame.

26. A spring plank saddle member com-

prising a body portion having depending flanges, adapted to embrace neighboring portions of a car truck side frame, the inner opposed faces of said flanges each being flared outwardly from an intermediate point thereof so as to provide fulcrums for permitting relative rocking movement of the saddle member with respect to the side frame.

27. A spring plank saddle member comprising a body portion having a spring seating surface, flanges depending from said body portion and adapted to embrace opposite side walls of a car truck side frame, and means including a depending longitudinally extending rib connected to said body portion and located between the depending flanges for reinforcing the spring seating surface.

28. A spring plank saddle member comprising a body portion having a spring seating surface, depending flanges provided on said body portion and adapted to embrace the inner and outer walls of a car truck side frame, means including a depending longitudinally extending rib integrally connected with said body portion and arranged between said depending flanges for reinforcing the spring seating surface, and means including an upstanding wall surrounding said spring seating surface, said wall being adapted to retain the springs in position and reinforce said body portion. 20 25 30

In testimony whereof I affix my signature.
